HUMIDOR

Wendell M. Hauch, New York, N. Y.; Flora F. Hauch administratrix of said Wendell M. Hauch, deceased

Application July 21, 1931. Serial No. 552,170

11 Claims. (Cl. 131—30)

This invention relates to new and useful improvements in containers for cigarettes, tobacco and other smoker's articles, and more particularly it pertains to a device of this character of the humidor type.

One object of the present invention is to improve the construction and mode of operation of humidors and so to construct such devices that they will effect a better conditioning of the articles carried therein.

A feature of the invention resides in a novel construction for securing and retaining a moistening element within the humidor.

Another feature of the invention resides in a novel construction of carrier for the moistening element aforementioned, and in the provision of means whereby the extent to which the moisture is given off thereby may be controlled.

Still another feature of the invention resides in a novel construction whereby the moistening element container together with its associated parts may be bodily removed from the humidor as occasion may require without damage or injury to the several parts thereof.

Still another feature of the invention resides in the provision of a novel construction whereby the moistening element, its container and associated parts may be carried wholly within the cover portion of the humidor, at the same time providing sufficient space within the humidor for the articles to be carried thereby.

Other features of the invention relate to certain novel and improved constructions, arrangement and combinations of parts hereinafter described and particularly pointed out in the claims, the advantages of which will be readily understood and appreciated by those skilled in the art.

The invention will be clearly understood from the accompanying drawings illustrating the invention in its preferred form and the following detailed description of the construction therein shown.

In the drawings,

Figure 1 is a vertical sectional view of a humidor constructed in accordance with the present invention.

Figure 2 is a sectional view of the cover taken on the line 2—2 of Figure 1, certain of the parts being shown in plan.

Figure 3 is a horizontal sectional view taken on the line 3—3 of Figure 1.

Figure 4 is a detail perspective view partly broken away illustrating the moistening element and valve member.

Figure 5 is a top plan view illustrating a modified form of the invention, and;

Figure 6 is a vertical sectional view taken on the line 6—6 of Figure 5.

Referring specifically to the drawings, the 60 humidor consists of a body 10 and a cover 11, the cover being removably associated with the body 10. Suitable partition devices such as 12 may be employed to divide the interior of the 65 humidor into a plurality of compartments although in certain instances, these partitions may not be desirable and for this reason they are constructed to be readily removable from the body 10. The cover 11 is provided with a handle portion 13 which serves as a grip which may be grasped for the purpose of manipulation of the cover.

In the illustrated embodiment of the invention, 15 designates a moistening element container and this container is preferably cylindrical in form and is provided with an opening or elongated slot 16 extending from the top thereof to a point closely adjacent the bottom thereof and located in the side walls. This slot 16 has two functions; first, it provides a resiliency 75 in the walls of the moistening element container 15 and secondly, it provides communication between the interior of the moistening element container 15 and the interior of the humidor. Means is provided for controlling the size of the 80 slot 16, and in the present embodiment of the invention this means comprises a valve member 17 which is preferably of sufficient resiliency to cause a relatively tight sliding fit with the interior of the moistening element container 15. 90 This valve member 17 consists of a single piece of material and its ends are spaced from each other as indicated at 18 in the drawings. One of the ends of the valve member 17 is provided with a small lug or projection 19 which occupies 95 a position in the slot 16 and projects therethrough to provide an operating member for the valve member 17. By means of this projecting member 19, the valve member 17 may be rotated within the moistening element container 100 15 and may be positioned therein to vary the size of the opening 16, and thus control the extent to which the moisture is given off into the interior of the humidor from a moistening element carried by the moistening element container.

The reference numeral 20 indicates a moistening element. This device may be of any desired type and in the present illustration is depicted as a clay tablet which is adapted to be subjected to water or other suitable fluid and thereafter 110

inserted in the moistening element container 15 and within the valve member 17 when the latter is employed, the moistening element container is of such form that it will without change in 5 form take any type of moistening element. Means is provided to position the moistening element 20 and in the present illustration of the invention, this means consists of projections or the like 21 struck inwardly from the valve member 17 and 10 adapted to engage or nearly engage the moistening element 20 and prevent movement and consequent rattling thereof within the moistening element container. At the same time these projections provide adequate space for circulation of 15 air between the moistening element and the walls of the valve member. As will hereafter appear, this valve member may, if desired, be eliminated when control of the moisture is not desired, in which instance, the projections 21 may be provided directly in the side walls of the moistening 20 element container.

Means is employed to retain the moistening container in position in the humidor, and in the present embodiment of the invention this means 25 consists of a resilient member 25. This member 25 has a main body portion 26 from which a plurality of arms 27 project. In the present embodiment of the invention there are three of these arms 27 and they are curved as best illustrated 30 in Figure 1 to provide a sufficient amount of resiliency to retain the member within the cover in a manner to be hereinafter described. The main body portion 26 of the resilient member 25 is recessed as at 27' to provide a channel like portion 28, the open side of which is disposed inwardly of the member 26.

The arms 27 of the resilient member 25 are adapted to engage a shoulder or the like 29 formed in the cover 11, and in this form of the invention, this shoulder extends entirely around the 40 cover.

When it is desired to place the resilient member 25 in the cover, it is only necessary to place the same therein and subject it to light pressure 45 when the free ends of the arms 27 snap behind the shoulder 29 and the member 25 is retained in position through the medium of its own resiliency.

The open upper end of the moistening element container 15 is provided with an annular bead or 50 the like 30, and this annular bead is adapted to be received within the channel 28 to suspend the moistening element container within the cover.

Thus it will be apparent that the resilient member 25 may be snapped into position in the cover and the moistening element container 15 due to 55 the resiliency of its walls provided by the notched or cut out portion 16 may be removably engaged with the channel 28 of the resilient member 25.

When it is desired to remove the moistening element container, a slight pull thereon will separate it from the resilient member 25, and the 60 resilient member 25 may be removed if desired merely by springing one of the legs 27 thereof, or the resilient member 25 may be removed before the moistening element container is detached therefrom if desired.

In that form of the invention illustrated in 70 Figures 5 and 6, the resilient member 25 and the moistening element container are of the same type as that employed in the form of the invention illustrated in Figures 1 to 4. In this modified form of the invention, however, the valve member has been eliminated and the continuous 75 or annular shoulder 29 of the cover 11 is re-

placed by separate or individual shoulders such as 40 which are provided at suitably spaced distances to receive the ends of the legs 27 of the resilient member 25. These shoulders are formed by forming recesses or the like 42 in the cover which recesses are of a width substantially the same as the width of the legs 27 of the resilient member 25 and said recesses are adapted to receive the legs of the resilient member 25 when the latter is snapped into position in the cover.

It has been found in actual practice that this construction is quite as efficient as that shown in the preferred form of the invention and this last mentioned construction also lends itself readily to effective ornamentation of the cover 11 as 80 is illustrated in Figure 5. The recesses 42 are of approximately the same contour as the resilient member 25 although as best illustrated in Figure 6, the resilient member 25 does not engage 85 the entire walls of the recess.

From the foregoing, it will be apparent that the present invention provides a highly efficient novel construction whereby the moistening element container may be readily attached and detached with 90 relation to the cover and that the humidor may 100 be used either with or without the moistening device. Furthermore, the construction of the present invention provides for complete removal of the means which carries or secures the moistening element container to the cover. Furthermore, since the member 25 is retained within the 105 cover solely by engagement of the free ends of the resilient legs 27 with one or more shoulders formed in the cover, a large latitude of cover form and ornamentation may be resorted to without necessitating any change in the construction of either the moistening element container or the member 25.

Having thus described the invention, what is 110 claimed as new and what it is desired to secure 115 by Letters Patent of the United States, is:

1. A humidor comprising a body, a cover therefor, a container for a moistening element, and means for removably attaching the moistening element container to the cover, said means comprising a resilient member interposed between the cover and the moistening element container, said means having a recess for the reception of the moistening element container.

2. A humidor comprising a body, a cover therefor, a resilient member removably engageable with the cover, and a container for a moistening element removably carried by said resilient member, said moistening element container having resilient side walls to permit of its removable attachment with the resilient member.

3. A humidor comprising a body, a cover therefor, an inwardly disposed shoulder extending annularly of said cover, a resilient member having removable engagement with said shoulder, and a container for a moistening element removably carried by said resilient member.

4. A humidor comprising a body, a cover therefor, an inwardly disposed shoulder extending annularly of said cover, a resilient member having an annular channel, said resilient member having removable engagement with said cover, a moistening element container carried by said cover, and an annular bead carried by said moistening element container, and adapted for reception in the afore-mentioned annular channel to secure the moistening element container to said resilient member.

5. A humidor comprising a body, a cover therefor, said cover having a plurality of recesses

formed therein, said recesses presenting a plurality of inwardly disposed shoulders, a resilient member having arms the free ends of which are receivable in said recesses in engagement with 5 said shoulders to retain said resilient member in place in the cover, and a moistening element container removably carried by said resilient member.

6. A humidor comprising a body, a dome shaped cover therefor, a shoulder formed on the interior of said dome shaped cover, a resilient member adapted to be sprung into said dome shaped cover and having engagement with said shoulder, and a moistening element container 10 removably carried by said resilient member.

7. A humidor comprising a body, a cover therefor, a shoulder formed on said cover and projecting inwardly thereof, a resilient member comprising a main body portion having an annular 20 groove therein, a plurality of extending portions adapted to engage behind said shoulder to retain the resilient member in position in the cover, a moistening element container and an annular bead carried by the container and engageable 25 to the annular channel to secure the container to the resilient member.

8. A humidor comprising a body, a cover therefor, a moistening element container comprising a cup-like member having an open end, and a portion cut out of the side walls thereof to lend 30 resiliency to said side walls, a bead adjacent the open end of the cup-like member, and means carried by the cover for the reception of the bead of the moistening element container to secure 35 the moistening element container in position in

the cover, said last mentioned means comprising a resilient member removably carried by the cover.

9. A humidor comprising a body, a cover therefor, said cover having a plurality of recesses formed in its inner surface, a moistening element container, and means for removably attaching said moistening element container to the cover, said means comprising a resilient member having a main body portion formed with a depressed portion to receive the moistening element container, and a plurality of arms extending from said resilient member and adapted to be received in said recesses. 80

10. A humidor comprising a body, a cover 85 therefor, said cover having a plurality of recesses formed in its inner surface, a resilient moistening element container, and means for attaching said moistening element container in said cover, said means comprising a resilient member having a centrally disposed recess for the reception of an end of the resilient moistening element container, and arms projecting from the resilient member for removable engagement with the cover. 90

11. A humidor comprising a body, a cover therefor, a moistening element container having an opening in the side wall thereof, a valve element for controlling said opening, and a resilient member removably carried by said cover and maintained in position on the cover through the medium of its own resiliency, said resilient member having means for removable engagement with the moistening element container. 105
